PATENTED JUNE 16, 1903.

J. S. KLEIN, DEC'D.

E. E. KLEIN, ADMINISTRATRIX.

WATER COOLED ROD AND PISTON.

APPLICATION FILED MAY 18, 1902.

NO MODEL.

UNITED STATES PATENT OFFICE.

JOHN S. KLEIN, OF OIL CITY, PENNSYLVANIA; EMILY E. KLEIN ADMINISTRATRIX OF SAID JOHN S. KLEIN, DECEASED.

WATER-COOLED ROD AND PISTON.

SPECIFICATION forming part of Letters Patent No. 730,924, dated June 16, 1903.

Application filed May 19, 1902. Serial No. 108,087. (No model.)

To all whom it may concern.

Be it known that I, JOHN S. KLEIN, a citizen of the United States, residing at Oil City, in the county of Venango and State of Pennsylvania, have invented new and useful Improvements in Water-Cooled Rods and Pistons, of which the following is a specification.

This invention relates to water-cooled rods and pistons; and it consists in certain improvements in the construction thereof, as will be hereinafter fully described, and pointed out in the claims.

The purpose of the invention is to cool rods and pistons ordinarily used in gas-engines, and more particularly a rod used on multiple-cylinder gas-engines.

The invention is illustrated in the accompanying drawings, as follows:

Figure 1 shows a central longitudinal section of the device; Fig. 2, a section on the line 2 2 in Fig. 1; Fig. 3, a development of the surface of the core of a rod.

A marks the rod, which comprises the core a and outer shell or tube a'. The core is provided with the webs a², which form grooves between them through which the water may pass. These webs are in contact with the shell or tube a' and stiffen the rod as well as form the separate channels. The tube a' being very thin, water in the passages formed between it and the web is very close to the surface, so that the tube may be kept reasonably cool under very high temperature. Pistons B B' are arranged on the rod, the piston B operating in one cylinder and the piston B' in a second cylinder. (These cylinders are not shown.) Water is admitted at one end of the rod through the pipes C C' and is expelled from the rod through the pipes D D'. The rod is attached, by means of its core, to the part of the cross-head or other device E by any usual means. The pistons are provided with passages through which water from the rod circulates.

One of the important features of this invention is that separate passages lead to the separate pistons, thus compelling a complete circulation in the rod as well as a separate circulation for each piston. By this means the circulation for each piston may be so controlled as to keep it properly cooled. The scheme of

passages is shown in Fig. 3. Water entering at C passes into the passage a³ and water entering at C' passes into the passage a⁴. The passage a³ is closed at the first piston B and is connected with the lower end of the piston B by means of the passage b. The water passes into the hollow b' of the piston; out by the passage b² of the piston into the passage a⁵, and out by the pipe D. It will be noted that the passages a³, a⁵ are separated from the part of the rod beyond the piston B by means of the cross-partitions a¹¹, a¹². The water entering the passage a⁴ through c' is conveyed by that passage to the piston B. The web a² at the end of this passage is cut at a⁶, and the water is conducted in the double passage a⁷, a⁸ to the piston B'. It passes from the passages a⁷, a⁸ by means of the passage b³ of the piston into the hollow b⁴ of the piston, and from this hollow by the passage b⁵ through the passages a⁹, a¹⁰ and passage a¹⁰ to the outlet D'. A passage a⁶ connects the passages a⁸, a⁹. The purpose of spreading the passage a⁴ is to deliver water to the entire surface of the rod A between the pistons. The passages a⁷, a⁸ accomplish this on the intake and the passages a⁹, a¹⁰ on the exit end of the circuit. Any number of passages may be provided, and any number of pistons may be handled in the same way by simply connecting a sufficient number of passages at each piston to convey cooling fluid to the rod beyond this piston.

By making one of the passages leading to the piston b or b' extend to near the bottom of the hollow b' or b⁴ the piston may be emptied by pressure through the other passage or by attaching a pump to the passages directly connected therewith. This is an important feature where there is danger of freezing when the engine in which it is placed is out of use.

What I claim as new is—

1. A water-cooled rod comprising a web, core, and a tubular shell, the shell contacting with the edges of the webs and forming separate channels for the passage of water between the shell and the core.

2. A water-cooled rod comprising a web, core, and a tubular shell, the shell contacting with the edges of the web and forming separate channels for the passage of water between the shell and the core, in combination

with connecting-passages whereby water may be made to traverse the rod and be introduced into and expelled from the same point of the rod.

5. 3. The combination of a plurality of pistons; a rod connecting them; a source of fluid supply and exhaust; and passages through the rod independently connecting the pistons with said supply and exhaust.
10. 4. The combination of a piston; a rod on which said piston is mounted having a passage leading to said piston; a separate passage leading through said piston to a second piston mounted on said rod; and said second piston.
15. 5. The combination of a piston; a rod on which said piston is mounted having a passage leading to and from said piston; separate passages leading through said piston to and from a second piston mounted on said rod; and said second piston.
20. 6. The combination of the piston, a rod extending through said piston, said rod being provided with a passage leading to and from said piston, and an independent passage lead-

ing through said piston to a part of the rod beyond said piston, said passage leading through the piston being extended circumferentially at or near the piston.

7. The combination of a piston having passages leading near the bottom thereof; a rod on which said piston is mounted having passages connected with said passage in the piston.

8. The combination of the piston B, having the hollow b'; passages b b², therein; the piston B', having the hollow b⁴ and passages b³ b⁵, therein; the rod A, comprising the core a, having the web a², forming the passages a³ a⁵, connected with the passages b b² respectively, the passages a⁴ a¹⁰, by passages a⁶ a⁹, the passages a⁷ a⁸, connected with the passages b³ b⁵; and the shell a', on said core.

In testimony whereof I have hereunto set my hand in the presence of two subscribing witnesses.

JOHN S. KLEIN.
